UNITED STATES PATENT OFFICE

CHAUNCEY B. KELLER, OF KIMBALL, NEBRASKA

DITCHING AND GRADING MACHINE

Application filed March 25, 1930. Serial No. 438,789.

This invention relates to ditching and grading machines and has for one of its objects to provide a novel and a comparatively simple machine of this character which shall be self-propelled and especially adapted to be used in rural communities, through the medium of which ditches may be dug and roads graded within a comparatively short time, and which shall be adapted to be controlled at 10 the expenditure of comparatively little manual labor.

The invention has for a further object to provide a machine of the character stated which shall be adapted to be operated close 15 to a bank and on level and on even surfaces and which shall be adapted to distribute the dirt excavated thereby over the desired portion of the road being graded or into dump wagons or cars so that it may be carried away 20 from the road.

The invention has for a further object to provide a machine of the character stated which shall embody a main frame supported at three points from the road by means including a chain tread tractor unit and wheels. 25

The invention has for a further object to provide a machine of the character stated wherein one of the wheels shall be arranged in advance of the tractor unit and the other laterally beyond and in a plane extending 30 between the tractor unit and the front wheel.

The invention has for a further object to provide a machine of the character stated wherein the main frame shall be pivotally connected to the tractor unit and so connected to the wheels as to permit it to be adjusted with respect to said parts to effect the levelling thereof when moving over irregular surfaces and to regulate the effective cutting depth of its excavating wheel. 40

The invention has for a further object to provide a machine of the character stated which shall embody an endless conveyor which 45 shall extend upwardly and laterally beyond one side of the machine and on to which the rotary excavating wheel shall deliver the excavated dirt, and which shall embody means through the medium of which the main frame may be adjusted upon the tractor unit and

wheels without altering the inclination of the conveyor.

The invention has for a still further object to provide a machine of the character stated which shall embody means arranged at the outer or discharge end of the conveyor and adapted to distribute the excavated dirt over the road, the means being adjustable to permit the excavated dirt to be distributed over any selected portions of the road, said means being also adapted to be employed for the purpose of delivering the excavated dirt into dump wagons or cars.

With the foregoing and other objects in view, the nature of which will appear as the description proceeds, the invention consists in the construction, combination and arrangement of parts hereinafter fully described and claimed, and illustrated in the accompanying drawings, wherein:

Figure 1 is a view in side elevation of the ditching and grading machine;

Figure 2 is a sectional view taken on the vertical plane indicated by the line 2—2 of Figure 1;

Figure 3 is a top plan view of the machine;

Figure 4 is a view partly in rear elevation and partly in vertical section of the rotary excavating wheel of the machine and the means for supporting and operating the same;

Figure 5 is a sectional view taken on the vertical plane indicated by the line 5—5 of Figure 4;

Figure 6 is a sectional view taken on the horizontal plane indicated by the line 6—6 of Figure 4;

Figure 7 is a view in side elevation of one of the bearings for the excavating wheel supporting shaft;

Figure 8 is a view partly in top plan and partly in horizontal section of the conveyor and the main frame adjusting means;

Figure 9 is a sectional view taken on the vertical plane indicated by the line 9—9 of Figure 8;

Figure 10 is a sectional view taken on the vertical plane indicated by the line 10—10 of Figure 9, and

Figure 11 is a sectional view taken on the

vertical plane indicated by the line 11—11 of Figure 2.

The ditching and grading machine comprises a main frame 1 which is supported at 5 its rear end by a tread tractor unit 2, and at its front end by a wheel 3 and at one side by a wheel 4. The tractor unit 2 may be of any well known or appropriate construction, and the main frame 1 is pivotally connected, 10 thereto, as at 5. The main frame 1 is provided at its front end with a vertical sleeve 6 which rests upon a yoke 7 and rotatably and slidably receives a spindle 8. The front wheel 3 is journaled in the yoke 7, and the 15 spindle 8 is secured to and extends upwardly from the yoke. The side wheel 4 is journaled in a yoke 9, and secured to and extending upwardly from this yoke is an open frame 10 which is connected to the main frame 1 by bars 11, the bars being pivoted, as at 12, 20 to the main frame and as at 13 to the wheel frame. The wheel 4 is located at the inner side of the main frame 1 between the front wheel 3 and tractor unit 2, and these parts, 25 together with the front wheel 3, provide a three point support for the main frame.

An internal combustion motor 14, and a seat 15 are mounted upon the main frame 1 above the tractor unit 2. The motor 14 may 30 be of any well known or appropriate construction, and drives a main shaft 16 which is arranged at the outer side of and extends longitudinally of the main frame 1. Any suitable means, not shown, may be employed 35 for establishing an operative connection between the motor 14 and drive shaft 16.

The drive shaft 16 is journaled in bearings 17 on the main frame 1, and secured to the rear end thereof is a worm wheel 18 which 40 meshes with a worm 19 on a shaft 20. This shaft extends transversely of the main frame 1 and is journaled in bearings 21. The tractor unit 2 includes a drive shaft 22 which is driven from the shaft 20 by a sprocket chain 45 23 which passes over a sprocket wheel 24 on the shaft 20 and a smaller sprocket wheel 25 on the pivot 5, and by a sprocket chain 26 which passes over a sprocket wheel 27 on the pivot and larger than the sprocket wheel 25 50 and over a sprocket wheel 28 on the shaft 22 and larger than the sprocket wheel 27.

The main frame 1 is adapted to be rocked upon its pivot 5 to effect the raising or lowering of its front end, so as to vary the effective 55 cutting depth of the rotary excavating wheel 29 on the machine, by means which includes a rack 30 formed on the rear side of the spindle 8, and a pinion 31 fixed to a shaft 32 and meshing with the rack. The shaft 32 extends 60 from the sleeve 6 to a point beyond the inner side of the main frame 1, and is journaled in bearings 33. This shaft is adapted to be driven from the main shaft 16 by a shaft 34 which extends from the main shaft to a 65 point beyond the inner side of the main

frame 1, and by a shaft 35 which extends longitudinally of the main frame and is located at the inner side thereof. The shaft 34 is journaled in bearings 36 and is connected to the main shaft 16 by beveled gears 37. The 70 shaft 35 is journaled in bearings 38 and has splined thereto a sleeve 39.

A beveled gear 40 is fixed to the rear end of the sleeve 39, and a beveled gear 41 is fixed to the front end thereof. Any suitable means, 75 not shown, may be provided for shifting the sleeve 39 on the shaft 35 so as to move one or the other of the gears 40 and 41 into engagement with a beveled gear 42 fixed to the shaft 34, and said means may be employed to maintain both of the gears 40 and 41 out of engagement with the gear 42. The shaft 35 is connected to the shaft 32 by a worm 43 fixed to the shaft 35 and meshing with a worm wheel 44 fixed to the shaft 32. When one of the gears 40 and 41 is in engagement with the gear 42, the pinion 31 is turned in a direction to lower the front end of the main frame 1, and when the other of the gears 40 and 41 is in engagement with the gear 42, the pinion 90 31 is turned in a direction to raise the front end of the main frame 1. The main frame 1 is maintained in its adjusted position by the engagement between the rack 30, pinion 31, worm 43, and worm gear 44.

Means are provided for turning the front wheel 3 about the axis of the spindle 8 so as to effect the steering of the machine. This means comprises a shaft 45 which extends longitudinally of the main frame 1 and is journaled in bearings 46, a hand wheel 47 fixed to the rear end of the shaft and a worm 48 fixed to the front end of the shaft and meshing with a worm wheel 49 on the spindle 8. The worm wheel 49 is journaled upon the main frame 1, as at 50, and it is connected to the spindle 8 by a rib 51, the rib being carried by the spindle and slidably engaged with the worm wheel in order to establish a driving connection between the worm wheel and spindle and in order to permit the worm wheel to move with the main frame during the adjustment of the latter.

The digging wheel 29 extends transversely of the main frame 1, and is located thereon between the tractor unit and the front wheel 3 and it is also located forwardly of the side wheel 4. The excavating wheel 29 is rotatably supported upon the frame 1 by a shaft 52 which passes through the hub 53 of the digging wheel and through bearings 54 on the main frame. The digging wheel 29 is loose on the shaft 52, and the shaft is fixed in its bearings by screws 55. The digging wheel 29 includes an annular rack 56 concentrically related to the shaft 52, a pinion 57 fixed to the main shaft 16 and meshing with the rack 56, establishes a direct driving connection between the main shaft and the digging wheel 29. The excavating wheel 125 130

29 also includes an annular series of scoops or buckets 58 which are concentrically related to the shaft 52. The rack 56 and scoops or buckets 58 are secured to and extend rearwardly from a circular plate 59 which is in turn secured to the hub 53.

The scoops or buckets 58 comprise front side walls 60 which incline forwardly and in the direction of the rotation of the excavating wheel 29, arcuate outer walls 61 which extend rearwardly from the outer edges of the side walls, rear side walls 62 which incline rearwardly and outwardly from the rear edges of the outer walls, and rear end walls 63 which extend radially inward from the rear ends of the outer walls. The scoops or buckets 58 are provided at the front edges of their front side walls 60 with ground cutting lips 64.

20 The scoops or buckets 58 are fully open at their inner sides so as to discharge the dirt excavated thereby into an inclined chute 65 which is fixed, as at 66, to the main frame 1. A semi-circular plate 67, which is secured, as at 68, to the main frame 1 extends from the lowermost scoop or bucket 58 to a point above the chute 65, so as to prevent the scoops or buckets from discharging their loads until directly above the chute.

25 The chute 65 discharges on to an endless conveyor belt 69 which extends transversely of the main frame 1 from a point outwardly beyond the lower end of the chute to a point laterally beyond the inner side of the main frame. The belt 69 passes about an inner roller 70 and an outer roller 71, and the rollers are carried by shafts 72 and 73, respectively, which are journaled in the ends of side bars 74. The shaft 72 is operatively connected with the drive shaft 16 by means of reduction gears 72' and 16', the gear 72' being mounted on the shaft 72 and the gear 16' being mounted on the shaft 16 and meshing with the gear 72'. The side bars 74 are pivoted at their inner ends, through the medium of the shaft 72, in bearings 75 fixed upon the main frame 1. The bars 74 carry rollers 76 upon which the upper run of the belt 69 rests, and they also carry a roller 77 upon which the lower run of the belt rests.

30 The belt 69 extends in an upwardly and inwardly inclined position from the main frame 1, and it is supported in this position by cables 78 which are wound about drums 79 and secured, as at 80, to the bars 74. The drums 79 are fixed to a shaft 81 which is journaled in bearings 82 on the upper end of the caster wheel frame 10. The bars 74 pass through the frame 10, and are connected to the vertical members of the frame by slides 83.

35 A shaft 84 is journaled in a bearing 85 secured, as at 86, to the main frame 1, and it is journaled in a bearing 87 fixed to the upper end of the frame 10. The shaft 84 is con-

nected at its outer end to the shaft 81 by a worm 88 fixed to the shaft 84 and meshing with a worm gear 89 fixed to the shaft 81. The shaft 84 is provided at its inner end with a hand wheel 90 to enable it to be readily turned in one direction to effect an increase in the angle of the belt 69 with respect to the horizontal or in the opposite direction to effect a decrease in the angle of the belt.

40 The conveyor belt 69 discharges into a distributor 91 which is arranged below the outer or upper end thereof and is supported from the bar 74 by bracket arms 92. The distributor 91 extends rearwardly and downwardly from the upper end of the belt 69 and increases in width in the direction of its rear end. The distributor 91 comprises a bottom wall 93, side walls 94, and is fully open at its upper side. Partitions 95 are arranged within and extend longitudinally of the distributor 91. The partitions 95 are pivoted at their rear ends, as at 96, to the bottom wall 93 of the distributor 91 so as to permit them to be adjusted toward and away from each other and toward and away from the side walls 94 of the distributor, and thus enable the excavated dirt to be distributed over selected portions of the road. If the excavated dirt is not to be distributed over the road, the distributor 91 may be used to evenly distribute the dirt over the bottom of a truck, car or the like. The bottom wall 93 of the distributor 91 is provided near its rear end with openings 97 in which are arranged pins 98 employed for the purpose of securing the partitions 95 in their adjusted positions.

45 As the bars 11 are pivotally connected to the main frame 1 and to the frame 10, the main frame is supported by the wheel 4 for adjustment about the longitudinal axis of the machine. The main frame 1 is adapted to be adjusted in this manner without altering the inclination of the conveyor belt 69, by a means which comprises vertical rack bars 99 which are pivoted at their lower ends, as at 100, to the main frame 1. The rack bars 99 and their pivots 100 are located inwardly of the pivot 72 of the bars 74, and a shaft 101, which extends transversely of and is journaled in these bars, is provided at its ends with pins 102 which mesh with the rack bars 99. A shaft 103, which extends transversely of the main frame and is journaled in a bearing 104, is provided at its inner end with a hand wheel 105 and at its outer end with a worm 106, the worm meshing with a worm wheel 107 on the shaft 101. As the bars 74 are pivoted to the main frame 1 and suspended from the wheel frame 10, and as the shaft 101 is journaled in the bars, the rotation of the shaft through the medium of the hand wheel 105 will cause the rack bars 99 to move downwardly or upwardly depending upon the direction of the rotation of the shaft. This movement of the rack bars 99 will turn the main frame 1

9335 9340 9345 9350 9355 9360 9365 9370

with respect to the longitudinal axis of the machine, with the result that the main frame will be levelled and supported in such position by the tractor unit 2 and the wheels 3 and 4. The upper and lower runs of the conveyor belt 69 are supported immediately above and below the shaft 100 and 101 by rollers 108 which are supported from the bars 74.

10 It should be understood from the foregoing description, taken in connection with the accompanying drawings, that the excavating wheel 29 will be rotated during the forward movement of the machine, that the dirt from the scoop or buckets 58 of the excavating wheel will be directed on to the conveyor belt 69 by the chute 65, that the conveyor belt will deliver the dirt to the distributor 91, and that the distributor may be employed for directing the dirt on to the selected portions of the road or into a car or truck. It should also be understood that the main frame may be readily adjusted on the tractor element 2 and the wheels 3 and 4 to regulate the effective cutting depth of the scoops or buckets 58 and to effect the levelling of the main frame, and that this may be done without altering the inclination of the conveyor belt 95. It should still further be understood that the machine is simple and easily controlled and adjusted at the expenditure of comparatively little manual effort.

While I have described the principle of the invention, together with the structure which I now consider the preferred embodiment thereof, it is to be understood that the structure shown is merely illustrative and that such changes may be made, when desired, as fall within the scope of the invention as claimed.

I claim:—

1. A ditching and grading machine, comprising a main frame, front and rear supports for the frame, a side support, a conveyor connected to the frame and extending laterally and upwardly therefrom to a point beyond the side support, means supporting the conveyor from the side support, adjusting means connected to the frame and conveyor, an excavating wheel journaled on the frame and discharging on to the conveyor, and means for operating the conveyor and excavating wheel.

2. A ditching and grading machine, comprising a main frame, a tractor unit, means pivotally supporting the rear end of the frame from the tractor unit, a front wheel, means connecting the front end of the frame to the front wheel for vertical adjustment with respect thereto, means carried by the frame and cooperating with said means and operable to permit said adjustment of the frame, a side support, a conveyor connected to the frame and extending laterally and upwardly therefrom to a point beyond the side

support, means supporting the conveyor from the side support, adjusting means connected to the frame and conveyor, an excavating wheel journaled on the frame and discharging on to the conveyor, and means for operating the tractor unit, conveyor and excavating wheel.

3. A ditching and grading machine, comprising a main frame, a tractor unit, a front wheel, means connecting the frame to the tractor unit and wheel to permit it to be adjusted with respect thereto, means for adjusting the frame, a side support, a conveyor connected to the frame and extending laterally and upwardly therefrom to a point beyond the side support, means supporting the conveyor from the side support, adjusting means connected to the frame and conveyor, an excavating wheel journaled on the frame and discharging into the conveyor, and means for operating the tractor unit, conveyor and excavating wheel.

4. A ditching and grading machine, comprising a main frame, a tractor unit, a front wheel, means connecting the frame to the tractor unit and wheel to permit it to be adjusted with respect thereto and to permit the wheel to be turned, means for adjusting the frame, means for turning the front wheel, a side support, a conveyor connected to the frame and extending laterally and upwardly therefrom to a point beyond the side support, means supporting the conveyor from the side support, adjusting means connected to the frame and conveyor, an excavating wheel journaled on the frame and discharging on to the conveyor, and means for operating the tractor unit, conveyor and excavating wheel.

5. A ditching and grading machine, comprising a main frame, a propelling unit, a front wheel, means connecting the frame to the propelling unit and wheel to permit it to be adjusted with respect thereto, means for adjusting the frame, a side wheel, a vertical frame mounted on the side wheel, a conveyor pivoted at one end to the main frame and extending laterally and upwardly therefrom and through said second frame, means adjustably supporting the conveyor from said second frame, adjusting means connected to the main frame and conveyor, an excavating wheel journaled on the main frame and discharging on to the conveyor, and means for operating the propelling unit, conveyor and excavating wheel.

6. A ditching and grading machine, comprising a main frame, front and rear supports for the frame, a side wheel, a vertical frame mounted on the side wheel, a conveyor pivoted to the main frame and extending laterally and upwardly therefrom and through said second frame, means slidably connecting the conveyor to said second frame, means supporting the conveyor from said second frame

and adjustable to permit the inclination of the conveyor to be varied, means for adjusting said last means, adjusting means connected to the main frame and conveyor, an excavating wheel journaled on the main frame and discharging on to the conveyor, and means for operating the conveyor and excavating wheel.

In testimony whereof I hereunto affix my
10 signature.

CHAUNCEY B. KELLER.
